UNITED STATES PATENT OFFICE.

FRANCIS M. HESS, OF CHICAGO, ILLINOIS.

DISTILLATE DISTRIBUTOR FOR HYDROCARBON DISTILLATION SYSTEMS.

Original application filed April 29, 1922, Serial No. 557,421. Divided and this application filed November 22, 1926. Serial No. 149,915.

This invention relates to the art of hydrocarbon distillation, and the present application constitutes a division of the application forming the basis of Letters Patent No. 1,608,741 granted to me on the 30th day of November, 1926.

In my aforesaid patent I have disclosed a distillation plant comprising a single large vapor box so organized and constructed as to permit fractional distillation from a plurality of units of which it is composed, the several units being formed with hollow conduit walls between which the crude material flows, and through which superheated steam, residuum and vapor pass in continuous flow, said hollow walls being continuous from top to bottom of the vapor box, with internal seals or traps between the several units which maintain the fractional distillates from the latter separate and distinct. Co-operating with said vapor box I have shown a single large multiple unit condenser and heat exchanger so divided as to provide a plurality of sealed chambers connected respectively with the several units of the vapor box; and in co-operation with said condenser and heat exchanger I have shown a multiple distributor so constructed as to route the fractions of distillate to any one or more of several lines so as to either maintain all of the fractions separate or effect any desired combination of two or more of the fractions.

The subject-matter of the present application relates to the multiple distributor hereinabove referred to; and the same, in one practical and efficient embodiment thereof, is illustrated in the accompanying drawing wherein—

Fig. 1 is a vertical section through the multiple distributor, and also through the multiple unit condenser and heat exchanger from which it receives the fractional distillates;

Fig. 2 is an enlarged vertical section through one unit of the distributor;

Fig. 3 is a horizontal section on the line 3—3 of Fig. 2; and

Fig. 4 is a vertical section of a leveling device employed in each of the flow lines from the condenser to the distributor.

Associated with the vapor box and the condenser and heat exchanger disclosed in my former patent above noted, and receiving the condensed fractional distillates and the incondensable gases directly from said con-

denser and heat exchanger, is a multiple distributor forming the subject-matter of this application, the purpose of which is to route the fractional distillates in any desired manner; either maintaining them entirely separate and distinct, or partially or entirely commingling them, according to the particular quality or qualities of the ultimate product or products desired from the distillation system. This distributor structure comprises a vertical cylinder 77 having upper and lower heads or closures 78 and 79, respectively, and equipped internally with a series of spaced centrally apertured bridge plates 80 attached to the cylinder wall. 60 Equally spaced around the inner surface of the cylinder are vertical delivery pipes 81, each of which is provided at points just above the bridge plates 80 with lateral branches or pour openings 82. On each of 70 the bridge plates 80 is an annular trackway 83 preferably carrying anti-friction bearings 84 co-operating with a similar track 85 on the lower side of an annular funnel 86. This funnel directly underlies the delivery 86 end of a horizontal pipe 76, which latter is carried into the distributor cylinder through a hole in the latter. The funnel 86 has a delivery spout 87 which, by rotation of the funnel, may be brought into register with 88 the pour opening or mouth 82 of any of the pipes 81. For turning the funnel 86, the latter is preferably equipped with an internal ring gear 88, best shown in Fig. 3, with which engages a pinion 89 fast on the lower 90 end of a vertical rod 90, this latter extending upwardly through the head 78 of the distributor cylinder and equipped with a hand wheel 91 on its upper end for turning the same. The number of rods, pinions and internal gears employed agrees, of course, with the number of distributing funnels in the distributor; five being shown in the present instance.

The several pipes 76 form outlet or delivery pipes from the several chambers of the combined condenser and heat exchanger shown at the left in Fig. 1, and forming the subject matter of a companion divisional application filed concurrently herewith, Serial No. 149,914. In the pipes 76 are preferably incorporated leveling devices L, one of which is shown in detail in Fig. 4, for regulating the height of the distillates in the chambers of the condenser, this leveling de- 110

vice being similar to that disclosed in Letters Patent No. 1,568,157 granted to me January 5, 1926.

From the foregoing it will be seen that by suitable manipulation of the rotary distributor funnels, the several fractional distillates from the condenser may all be routed through the respective delivery pipes 81, or any two or more fractions may be combined and sent off through a single delivery pipe, as desired. Any incondensable gases entrained with the condensates are vented through a pipe line Z at the top of the distributor shell 77.

15 I claim—

1. A distributor for routing fractional distillates, comprising a circularly grouped series of vertical discharge pipes each provided with a plurality of vertically spaced lateral branches, corresponding branches of the several pipes being located in the same horizontal planes, funnels rotatably mounted above and coaxially with the several horizontal groups of branches, respectively, and each having a discharge nozzle adapted to be brought into register, by a turning movement of said funnel, with any branch of its associated group, a corresponding series of delivery pipes for the material to be distributed having their discharge ends overhanging said funnels, and independent means for rotating the respective funnels.

2. A distributor for routing fractional distillates, comprising a circularly grouped series of vertical discharge pipes each provided with a plurality of vertically spaced lateral branches, corresponding branches of

the several pipes being located in the same horizontal planes, bridge plates disposed between said discharge pipes beneath the several horizontal groups of branches and each formed with a circular trackway, funnels rotatably mounted on said trackways and each having a discharge nozzle adapted to be brought into register with any branch of its associated group, a corresponding series of delivery pipes for the material to be distributed having their discharge ends overhanging said funnels, and independent manually operable means for turning the respective funnels on their trackways.

3. A distributor for routing fractional distillates, comprising a circularly grouped series of vertical discharge pipes each provided with a plurality of vertically spaced lateral branches, corresponding branches of several pipes being located in the same horizontal planes, bridge plates disposed between said discharge pipes beneath the several horizontal groups of branches and each formed with a circular trackway, annular funnels rotatably mounted on said trackways and each having a discharge nozzle adapted to be brought into register with any branch of its associated group, internal gears on said annular funnels, independent operating rods extending within the respective funnels and each carrying a pinion meshing with the internal gear of the latter, hand wheels on the said rods, and a corresponding series of delivery pipes for the material to be distributed having their discharge ends overhanging said funnels.

FRANCIS M. HESS.
